RIDER PROPELLED STILT

William K. Schauweker, Cleveland, Ohio

Application December 31, 1934, Serial No. 759,873

8 Claims. (Cl. 280—220)

This invention relates to a stilt and has for its object to provide such a device which is provided with a wheeled carriage element and rider operated propelling means.

With the foregoing and other and more limited objects in view which will become apparent as the description proceeds, the invention consists in the novel construction and arrangement of parts as hereinafter fully described and pointed out in the appended claims.

Fig. 1 is a side elevation of the preferred embodiment of my invention; Fig. 2 is a fragmentary rear elevation thereof; Fig. 3 is a fragmentary sectional view corresponding to a vertical section through the hub of the rear traction element; Fig. 4 is a fragmentary elevation of a modified form wherein the hand piece or standard is fixed with respect to the carriage element and the foot piece moves with respect thereto; Fig. 5 is a fragmentary horizontal sectional view corresponding substantially to the line 5—5 of Fig. 4 and Fig. 6 is a fragmentary detail view showing the handle 35 and its relation to the upright 10.

In the drawing, the numeral 10 indicates a standard or hand piece of a rider-propelled stilt embodying my invention, 11 indicates the carriage element generally and 12 indicates the foot piece. The movable parts of the carriage element 11 are carried on a plate 13. A front wheel 14 is suitably mounted for rotation on a hub carried by the lower forward corner of the plate 13. The rear wheel or traction element 15 is carried by a shaft 16 journaled in a suitable bearing 17 riveted or otherwise secured to the plate 13. Mounted for rotation on the shaft 16 is a drum 18 having flanges 19 and 20 providing a channel within which a flexible element 21 is adapted to be wound. The drum is provided with a cylindrical flange 22 forming one element of an ordinary overrunning clutch, the other element of which is formed by the end of the shaft 16 and rollers 23 interposed therebetween and held in position by a keeper 24. A spring 25 is interposed between the element 17 and the drum 18 for returning the drum to original position after it has been rotated by the unwinding of the flexible element 21.

The stilt or hand piece 10 is provided adjacent the lower end with a slot 26, the surface of which may be reinforced by a plate 27 having a corresponding slot. This slot receives headed members 28 adapted to work in said slot. The headed members may be provided with washers 29 for engagement with the edges of the slot to reduce

friction. Mounted on the stilt element 10 is a bracket element 30 carried by suitable brackets 31 and held in position by braces 32. The foot piece may be provided with a toe strap 33 for enabling vertically movable parts to be elevated by the rider. Attached to the lower end of the stilt element 10 is one end of the flexible element 21 which passes over an idler pulley 34 carried by the plate 11. The flexible element passes downwardly and is wound about the drum 18. The element 10 may be provided with a laterally extending handle 35 which may be adjustable by means of a series of openings 36 in the handle 10.

It will be clear that when the stilt element 10 and foot piece 12 are reciprocated vertically, the flexible element will alternately wind and unwind, imparting vertical motion to the traction element 15 as the stilt piece goes downwardly and rewinding as the stilt piece moves upwardly.

In Fig. 4, I have shown a modified form in which the stilt or hand piece 10 is fixed with respect to the plate 11 while the foot piece 12 is provided with an element 37 partially embracing the element 10 and slidably upwardly and downwardly thereon. A bent-over portion 37a of the element 37 is received in a rabbet formed in the corners of the element 10 adjacent the element 13. Attached to the lower surface of the element 37 is the end of the flexible element 21 which passes over the idler pulley 34 and to the drum 18 in the same manner as described in connection with the preferred embodiment.

While I have shown and described the present preferred embodiment of my invention, I wish it understood that I am not limited to the details but only in accordance with the appended claims and the prior art.

Having thus described my invention, what I claim is:

1. A rider propelled stilt comprising in combination, a carriage element, a stilt element including a standard adapted to be grasped by the hand of the rider and a footpiece, said stilt element being vertically, slidably connected to said carriage element, and means operated by vertical reciprocation of said stilt element with respect to said carriage element for propelling said carriage element.

2. A rider propelled stilt comprising in combination, a carriage element, a stilt element including a standard adapted to be grasped by the hand of the rider and a footpiece, said stilt element being vertically, slidably connected to said carriage element, and means operated by verti-

cal reciprocation of said stilt element with respect to said carriage element for propelling said carriage element, said carriage element including at least one wheel, an idler pulley above the hub thereof, a clutch associated with said hub, a flexible element passing over said idler pulley and means for causing said flexible element to drive said wheel through said clutch.

5 3. A rider propelled stilt comprising in combination, a carriage element, a standard adapted to be grasped by the hand of the rider for maintaining said carriage in upright position, a foot-piece mounted for vertical reciprocation with respect to said carriage element, and means operated by such vertical reciprocation for propelling said carriage, said carriage element including at least one wheel, an idler pulley above the hub thereof, a clutch associated with said hub, a flexible element passing over said idler pulley and means for causing said flexible element to drive said wheel through said clutch.

10 4. A rider propelled stilt comprising in combination, a carriage element, a stilt element including a standard adapted to be grasped by the hand 15 of the rider and a foot-piece, said stilt element being vertically, slidably connected to said carriage element, and means operated by vertical reciprocation of said stilt element with respect to said carriage element for propelling said carriage element, said carriage element including a plate, wheels carried thereby one in front of the other, one of said wheels being a traction wheel, an idler pulley carried by said plate above the hub of said traction wheel, a clutch associated with 20 the hub of said traction wheel, a flexible element passing over said idler pulley and means for causing said flexible element to drive said wheel through said clutch.

25 5. A rider propelled stilt comprising in combination, a carriage element, a standard adapted to be grasped by the hand of the rider for maintaining said carriage in upright position, a foot- 30

piece mounted for vertical reciprocation with respect to said carriage element, and means operated by such vertical reciprocation for propelling said carriage, said carriage element including a plate, wheels carried thereby one in front of the 5 other, one of said wheels being a traction wheel, an idler pulley carried by said plate above the hub of said traction wheel, a clutch associated with the hub of said traction wheel, a flexible element passing over said idler pulley and means for causing said flexible element to drive said wheel through said clutch.

10 6. A rider-propelled stilt comprising, in combination, a carriage element, a stilt element, a foot piece, cooperating vertically extending elements 15 carried by said foot piece and said carriage element whereby the former is vertically slidably mounted for vertical reciprocation with respect to the latter, said stilt element being carried by said carriage element and extending upwardly 20 therefrom a distance to be conveniently grasped by the hand of the user and capable of maintaining said carriage element in upright position.

15 7. A rider-propelled stilt comprising, in combination, a carriage element, a stilt element, a foot piece, cooperating vertically extending elements 25 carried by said foot piece and said carriage element whereby the former is vertically slidably mounted for vertical reciprocation with respect to the latter, said stilt element being fixedly secured to said carriage element.

20 8. A rider-propelled stilt comprising, in combination, a carriage element, a stilt element, a foot piece, cooperating vertically extending elements 35 carried by said foot piece and said carriage element whereby the former is vertically slidably mounted for vertical reciprocation with respect to the latter, said stilt element being fixedly secured to said carriage element and forming one 40 of said cooperating elements.

W. K. SCHAUWEKER.
